UNITED STATES PATENT OFFICE

2,601,150

APPARATUS FOR DRYING LEATHER AND
OTHER SHEET MATERIALGeorge H. Jennings, Cincinnati, Ohio, assignor
to Howes Leather Company, Inc., Boston, Mass.,
a corporation of Delaware

Application October 18, 1950, Serial No. 190,698

6 Claims. (Cl. 34—58)

1

This invention relates to apparatus for drying sheet material in smooth, unwrinkled condition and more particularly to stretching and drying heavy sheet material such as sole leather.

Heretofore it has been proposed to dry pieces of leather by rotating them edgewise at velocities high enough to stretch them into smooth condition by centrifugal force. However such attempts have not been successful for various reasons. The prior machines have either been too complicated or they damaged the leather or both.

Objects of the present invention are to provide apparatus which is simple and economical in construction, which will stretch and dry double bends and double shoulders of leather uniformly and quickly throughout their entire areas without damaging the leather and generally to improve the art of stretching and drying pieces of sheet material such as sole leather.

According to the present invention the apparatus comprises a rotatable shaft, a clamp for holding a piece of sheet material on the shaft between two faces which are approximately perpendicular to the axis of the shaft, and a ring mounted concentrically on the shaft adjacent to the clamp but offset therefrom lengthwise of the shaft, the diameter of the ring being substantially greater than that of the clamp and less than that of the aforesaid pieces so that a piece of material clamped between the faces may be draped over the ring and then, when the shaft is rotated, caused to extend out by centrifugal force in a plane perpendicular to the shaft without danger of the material becoming entangled. Preferably the ring is interconnected to the shaft by means of fan blades which are inclined in the direction to create a current of air toward the rotating piece of material. In the preferred embodiment another ring, preferably in the form of a perforated disc with rounded edge, is mounted concentrically on the shaft on the other side of the clamp to catch the material when it collapses as the shaft stops rotating. To permit the pieces to be mounted at or near their centers, the clamps are preferably located at opposite ends of the shaft with the rotating means therebetween. Preferably the shaft is disposed horizontally on a portable frame with its ends projecting from opposite sides of the frame.

2

For the purpose of illustration a typical embodiment of the invention is shown in the accompanying drawings in which:

Fig. 1 is a top plan view without any leather in place;

Fig. 2 is an end view;

Fig. 3 is a side elevation of one end of the apparatus showing in broken lines the position the leather occupies when draped over the supporting ring before the shaft starts rotating and also the extended position it occupies while the shaft is rotating;

Fig. 4 is a section on line 4—4 of Fig. 3;

Fig. 5 is a section on line 5—5 of Fig. 3; and

Fig. 6 is a plan view of a double bend piece of leather showing how it is perforated to fit the clamps.

The particular embodiment of the invention chosen for the purpose of illustration comprises a portable frame mounted on wheels 1. The base of the frame comprises longitudinal channel members 2 and transverse members 3. Extending upwardly from these base members 2 are inclined upright channel members 4 which are joined together at the top by a short longitudinal member 6. Intermediate their upper and lower ends the inclined members are interconnected by channel members 7. Mounted on each of the members 7 is a longitudinal channel 8 which is interconnected with the top member 6 by inclined braces 9 and with the ends of cross members 11 by oblique braces 10. Mounted on the other ends of the members 8 are cross members 11 which are tied to the inclined braces 9 by means of plates 12, all of these parts being secured together by welding. Bolted to the members 8 directly over the members 7 are bearings 13 for shaft 14 which extends through openings 16 in the cross members 11. Fast to the shaft 14 at its center is a pulley 17 which is driven through belt 18 by motor 19 mounted on the cross members 3 by means of a support 21 of well-known construction. The ends of the shaft 14 are supported in bearings 22 mounted on the outer faces of members 11.

The tip ends 23 of the shaft are reduced in diameter and mounted on each of these reduced ends are two clamps 24 and 26, a cupped disc 27 and a nut 28 to hold the parts on the shaft, the clamp 24 being fast to the shaft. The faces

3

of the two clamps have knurled portions 29 and 30 to grip the leather tightly and the clamp 24 has two projecting pins 31 fitting into openings 32 in the clamp 26 to prevent rotation of the clamp 26 relative to the clamp 24. The clamp 26 and the disc 27 have central openings to receive the reduced end 23 of the shaft 13. As shown in the drawings the disc 27 is preferably perforated to facilitate drying of the central portion of the hide. Fast to the shaft 14 immediately outside of each bearing 22 is a hub 36 carrying a ring 37 through the medium of spokes 38 in the form of fan blades.

In drying a double bend piece of leather such as shown in Fig. 6, openings 33 and 34 are provided, preferably along the center line of the double bend to receive the pins 31 and shaft 23. To apply a double bend to the shaft the clamp 26, disc 27 and nut 28 are removed, the hide is applied over the shaft 23 and pins 31 and then draped over the ring 37 in the position indicated at L in Fig. 3. Then the clamp 26, disc 27 and nut 28 are applied, the nut 28 being tightened sufficiently to hold the parts in place. Then the motor is started and as the shaft accelerates the hide stretches out from said position to the position indicated at L' in Fig. 3. The motor is driven in the direction to cause the fan blades to create a current of air against the central portion of the adjacent hide. Inasmuch as the central portion of the hide has a lower linear velocity through the air, it would tend to dry more slowly than the periphery except for the action of the fan blades which cause the hide to dry uniformly throughout its entire area. After the hide is stretched and dried the motor is stopped and the hide again collapses. If it collapses inwardly it falls over the ring 37 and if it collapses outwardly it falls over the disc 27.

It should be understood that the present disclosure is for the purpose of illustration only and that this invention includes all modifications and equivalents which fall within the scope of the appended claims.

I claim:

1. For drying pieces of sheet material, apparatus comprising a shaft, means for rotatably supporting the shaft, a clamp for holding a piece of sheet material on the shaft between two faces which are approximately perpendicular to the axis of the shaft, and a ring mounted concentrically on the shaft adjacent to the clamp, the diameter of the ring being substantially greater than that of the clamp but less than that of said pieces so that a piece of material clamped between said faces may be draped over said ring and then, when the shaft is rotated, caused to extend out by centrifugal force in a plane perpendicular to the shaft without danger of the material becoming entangled, said ring being offset from said plane lengthwise of the shaft so that there is a substantial space between the sheet material and the ring when the sheet is extended by centrifugal force.

2. For drying pieces of sheet material, apparatus comprising a shaft, means for rotatably supporting the shaft, a clamp for holding a piece of sheet material on the shaft between two faces which are approximately perpendicular to the axis of the shaft, a ring concentric with the shaft adjacent to the clamp but offset therefrom lengthwise of the shaft, the diameter of the ring being substantially greater than that of the clamp but less than that of said pieces

4

so that a piece of material clamped between said faces may be draped over said ring and then, when the shaft is rotated, caused to extend out by centrifugal force in a plane perpendicular to the shaft, and fan blades interconnecting the ring and shaft, the blades being inclined in the direction to create a current of air toward the rotating piece of material.

3. For drying pieces of sheet material, apparatus comprising a shaft, means for rotatably supporting the shaft, a clamp for holding a piece of sheet material on the shaft between two faces which are approximately perpendicular to the axis of the shaft, a ring mounted concentrically on the shaft on one side of the clamp, the diameter of the ring being substantially greater than that of the clamp but less than that of said pieces so that a piece of material clamped between said faces may be draped over said ring and then, when the shaft is rotated, caused to extend out by centrifugal force in a plane perpendicular to the shaft without danger of the material becoming entangled, and another ring mounted concentrically on the shaft on the other side of the clamp to catch the material when it collapses as the shaft stops rotating.

4. For drying pieces of sheet material, apparatus comprising a shaft, means for rotatably supporting the shaft, a clamp for holding a piece of sheet material on the shaft between two faces which are approximately perpendicular to the axis of the shaft, a ring concentric with the shaft adjacent to the clamp but offset therefrom lengthwise of the shaft, the diameter of the ring being substantially greater than that of the clamp but less than that of said pieces so that a piece of material clamped between said faces may be draped over said ring and then, when the shaft is rotated, caused to extend out by centrifugal force in a plane perpendicular to the shaft, fan blades interconnecting the ring and shaft, the blades being inclined in the direction to create a current of air toward the rotating piece of material, and another ring mounted concentrically on the shaft on the other side of the clamp to catch the material when it collapses as the shaft stops rotating.

5. For drying pieces of sheet material, apparatus comprising a shaft, means intermediate its ends for rotating the shaft, a clamp on each end of the shaft for holding a piece of sheet material between two faces which are approximately perpendicular to the axis of the shaft, a ring concentric with the shaft adjacent to each clamp but offset therefrom lengthwise of the shaft, the diameter of the rings being substantially greater than that of the clamps but less than that of said pieces so that pieces of material clamped between said faces may be draped over said rings and then, when the shaft is rotated, caused to extend out by centrifugal force in planes perpendicular to the shaft, and fan blades interconnecting each ring and shaft, the blades being inclined in the direction to create currents of air toward the rotating piece of material.

6. For drying pieces of sheet material, apparatus comprising a horizontal shaft, means for rotatably supporting the shaft, a clamp on each end of the shaft for holding a piece of sheet material between two faces which are approximately perpendicular to the axis of the shaft, a ring concentric with the shaft adjacent to each clamp but offset therefrom lengthwise of the shaft, the diameter of the rings being sub-

stantially greater than that of the clamps but less than that of said pieces so that a piece of material clamped between said faces may be draped over said rings and then, when the shaft is rotated, caused to extend out by centrifugal force in planes perpendicular to the shaft, and fan blades interconnecting each ring and shaft, the blades being inclined in the direction to create currents of air toward the rotating pieces of material.
